CLAIM

We claim the ornamental design for a traction motor case, as shown and described.

DESCRIPTION

FIG. 1 is a front perspective view of a traction motor case; FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a rear perspective view of the traction motor case on a motorcycle.

The broken lines are included for the purpose of showing environment that forms no part of the claimed design.
